UNITED STATES PATENT OFFICE

STANLEY B. CUMMINGS, OF CANTON, OHIO, ASSIGNOR TO THE HOOVER COMPANY, OF NORTH CANTON, OHIO, A CORPORATION OF OHIO

ABSORPTION REFRIGERATING SYSTEM

Application filed January 24, 1930. Serial No. 423,075.

This invention relates to the art of refrigerating and more particularly to an absorption refrigerating system in which a plurality of refrigerants are simultaneously evaporated to produce a cooling effect.

Continuous absorption refrigerating systems employing a single refrigerant in combination with an inert or neutral gas are well known. In such a system the inert gas is circulated between the evaporator and the absorber for the purpose of maintaining the total pressure in these parts the same as that in the other parts of the system although the partial pressure of the refrigerant changes. An example of such a system is found in the U. S. Patent to Geppert 662,690. As an improvement on this system it has previously been proposed to substitute a second refrigerating agent for the inert gas of the Geppert system so that both the main cooling agent and the auxiliary pressure equalizing agent may be condensed before they are introduced into the evaporator, the object being to increase the efficiency and the cooling effect of the system. Perhaps the best substances suggested for this purpose are ammonia and propane, these two refrigerants being condensable at about the same temperature and pressure and being practically immiscible.

In attempting to operate a system having two refrigerants, one of the chief difficulties encountered has resulted from the fact that it is difficult if not impossible to completely separate the two so long as they remain in a gaseous or vapor phase. Unless effectively separated, the refrigerants get into the condensers in which they do not belong and prevent successful operation of the apparatus.

An object of the present invention is to provide effective means for separating the refrigerants of such a system so that each may be condensed independently at the pressure existing within the system and at temperatures which may be considerably above that prevailing in the evaporator.

A further object of the invention is to provide a practical refrigerating system employing a plurality of refrigerants and in which all of the parts are in open communication

with one another so that nearly the same total pressure prevails throughout the system, the refrigerants mutually cooperating to reduce the partial pressure of each so that evaporation of both may take place to produce a cooling effect.

A further object is to provide a method of effectively separating the fluids of a refrigerating system so that they may be readily condensed.

Other objects and advantages reside in certain novel arrangements and construction of parts as will be apparent from the following description taken in connection with the accompanying drawings in which:

Figure 1 is a diagram of an absorption refrigerating system embodying certain novel features and illustrating one form of apparatus made in accordance with the principles of the invention and

Figure 2 is a diagrammatic showing of a modified form of system illustrating the principles of the invention.

Referring to Figure 1 of the drawings, the system is there shown as consisting of a generator or boiler G, rectifiers R₁ and R₂, condensers C₁ and C₂, evaporator E and an absorber-separator S as essential elements, these vessels being connected by suitable conduits, as shown. All of these parts may be made of steel. In general, they are cylindrical in shape so that ordinary seamless steel tubing may be used in manufacturing them.

The generator G comprises a hollow shell 10 having end closures or heads 11 and 12 at the top and bottom thereof. The lower end piece 12 is provided with an inverted cup 13 which is welded or otherwise secured to an opening therein and which is adapted to receive an electric cartridge heating element 14. Obviously a gas flame or other heating means may be employed in place of the electric heater. In normal operation, a solution of ammonia circulates through the generator. For conducting the solution into the generator a pipe 15 extends through the wall or shell 10 and is connected to a small coil of tubing 16 which is wrapped around the inverted cup 13. The upper end of the coil 16 is connected to a small vertically extending

pipe 17 the upper end of which is reversely bent as shown. By this means when current passes through the electric heater 14, bubbles of ammonia gas are generated in the coil 16 and as they rise through the pipe 17 lift or pump the solution into the main body of the generator, this action being similar to that found in certain types of household coffee percolators. A similar arrangement of a gas lift pump of this nature in a refrigerating system is shown and described in U. S. Patent to Altenkirch 1,728,742.

Aside from the ammonia gas generated in the gas lift pump, an additional amount of gas may be driven off by the application of heat from the electric heater to the main portion of the generator. The gas passes upwardly through an opening in the closure 11 and into the rectifier R_1 which is provided with suitable baffles, as shown, for removing water vapor which is driven off with the ammonia. An additional amount of water vapor is removed in the rectifier R_2 . This device comprises the central pipe 19 to which fins for radiating heat are welded or otherwise secured. The upper end of rectifier R_2 is connected to condenser C_1 through the pipe 21. A valve 22 is provided in the pipe 21 which may be opened to charge the machine.

As ammonia is driven off from the water, the weak ammonia solution is conducted away from the generator through the conduit 23.

The condensers C_1 and C_2 , referred to above, may be of any suitable construction. They are shown for the purposes of illustration as consisting of coils of tubing, the coil C_2 being the larger of the two. The coils are immersed in a tank 24 through which cooling water is adapted to circulate, inlet pipe 25 and outlet pipe 26 being provided for this purpose. Since the condenser C_2 is the larger of the two, the temperature therein will be more nearly that of the cooling water.

The lower ends of the condensers C_1 and C_2 are connected to the evaporator E by pipes 27 and 28 each of which is provided with a suitable valve.

The evaporator E is so constructed that the liquids entering through the pipes 27 and 28 do not mix so long as they are in the liquid phase but each liquid is exposed to the vapor phase of the other. For a full disclosure of this evaporator reference may be had to the copending application of Rudolph S. Nelson, Serial No. 423,125 filed Jan. 24, 1930, entitled "Evaporators for refrigerating systems" wherein this evaporator is more fully disclosed and claimed. As herein shown it consists of a cylindrical shell 29 having end pieces or heads 30 and 31 at the upper and lower ends. The pipes 27 and 28 extend through the head piece 30 and terminate a short distance above the bottom of cups 32 which have overflow outlets near their upper ends. Liquids entering through

the pipes 27 and 28 trickle down over separate sets of baffle plates so that each is exposed to the vapor phase of the other. This causes evaporation accompanied by the extraction of heat from the surroundings to produce a cooling effect. The vaporized fluids are conducted out of the evaporator through the conduit 33 extending through the lower end piece 31.

An important feature of the present invention resides in the arrangement and construction of the absorber-separator vessel S together with means for cooling the lower portion and heating the upper portion thereof. Like the generator and evaporator the separator S is preferably composed of a shell 35 provided with upper and lower end closures 36, 37. There are four conduits communicating with the interior of this vessel. Conduit 33 passes through the wall of the shell near its lower end for connecting the vessel to the evaporator. Conduit 38 having a valve 22' therein similar to valve 22 connects the upper end of the vessel to the condenser C_2 . Conduits 39 and 41 terminating at the bottom and side of the vessel respectively connect it with a heat exchanger 40.

This heat exchanger is of the conventional double coil type. One end of the inner coil is connected to the pipe 39. The other end is connected to the gas lift pump 16. The outer tube of the heat exchanger is connected to pipes 41 and 42. The pipe 42 is adapted to convey solution into the heat exchanger from a heating jacket 44 surrounding the upper portion of the separator, this jacket being supplied with solution by the pipe 23. By this construction solution passing from the generator G through the conduit 23 may heat the upper portion of the separator by convection from the generator. Since it is likely that some gas may collect in the jacket 44, it may be advisable to provide a bleed pipe for conveying it back to the generator. A pipe for this purpose is shown at 43.

For cooling the lower portion of the absorber, a jacket 45 is provided, this jacket having a connection 46 for supplying cooling water thereto. From the jacket 45, the water goes through the pipe 25 to the tank 24.

For aiding in the conduction of heat away from the lower portion of the separator and for facilitating the absorption of ammonia, the separator may be partially filled with steel wool 47 or other heat conducting material adapted to break up gases entering through the pipe 33 from the evaporator into small bubbles. The steel wool may be held in place by perforated plates 48.

The liquid levels in the various parts of the apparatus are critical to successful operation of the machine. For this reason it is necessary that the various parts be positioned approximately as shown in the drawings.

This will be more apparent after considering the operation of the system.

The apparatus may be charged and operated as follows:

5 A quantity of ammonia solution is placed in the generator G and separator S through suitable valves, not shown, until the same has filled the same up to approximately the level of pipe 23. While the concentration 10 of the ammonia solution may vary, it is deemed advisable to use one of relatively low concentration preferably not over 15% by weight. As the solution is being placed in these vessels, valves 22 and 22' in the conduits 21 and 38 should be open to the atmosphere so that air in the machine may escape. 15 Ammonia gas may then be forced through the apparatus in the usual manner to sweep out any remaining air. The valve 22 may then be closed and liquid propane fed into the conduit 38 through the valve 22' therein. This liquid propane collects in the separator and causes the solution level in the generator to rise slightly but since propane 20 has a specific gravity much lower than that of the ammonia solution, it floats on top of the solution in the separator. The quantity of propane placed into the system should be somewhat more than that necessary to occupy the portion of the separator opposite the heating jacket 44 plus that necessary to 25 fill one of the cups 32 and form a column in the pipe 27, liquid propane normally being in these parts to this extent during operation of the system.

After the machine is so charged heat may be applied to the generator by causing current to pass through the electric heater. This causes circulation of the ammonia solution 40 and since the heat exchanger and other pipes offer some resistance to flow, the liquid levels in the generator and separator assume the position approximately as shown in dotted lines. Ammonia vapor or gas is delivered 45 to the condenser C₁ and propane vapor is delivered to condenser C₂. The heat necessary for the evaporation of propane which has collected in the upper portion of the separator is supplied by the warm ammonia solution 50 circulating through the jacket 44. Since the condensers C₁ and C₂ are maintained at a temperature considerably below that of the boiler and upper portion of the separator, the two refrigerants condense in their respective condensers and flow into the cups 55 32 of the evaporator. As the liquids fed into the evaporator overflow from the cups and trickle down over the plates provided therein, simultaneous evaporation takes place, the 60 vapor of each refrigerant exerting its pressure independently of the other so that although the total pressure in the evaporator is slightly greater than elsewhere in the system, the partial pressure of each refrigerant 65 vapor is much less. As evaporation takes

place heat is taken up from the surroundings to produce a cooling effect. At this time the total pressure in the evaporator becomes slightly larger than elsewhere in the system and causes the formation of liquid columns in the pipes 27 and 28 as the refrigerants 70 continue to condense. Upon the pressure in the evaporator becoming large enough to overcome the slight excess pressure due to the liquid column head in the separator bubbles of ammonia and propane are forced 75 into the lower portion of the separator through the pipe 33. As these bubbles mix with the weak solution coming to the separator through the pipe 41 the ammonia content is absorbed, this causing an increase in the percentage of gaseous propane in the bubbles and since the bottom portion of the separator is maintained cold by the cooling jacket 45 the propane condenses at this point. 80 As the propane condenses it rises to the upper portion of the separator where it is again driven off by heat from the heating jacket 85 44 thus completing its cycle.

The ammonia which is absorbed in the solution in the lower portion of the separator is conducted through the pipes 39, the inner tube of the heat exchanger 40, the pipe 15, gas lift pump 16 and pipe 17, back into the generator where it is again driven off 90 to complete its cycle.

The solution thus deprived of ammonia returns to the separator through the pipe 23, jacket 44, pipe 42, outer tube of heat exchanger 40 and pipe 41. Effective separation of the refrigerants results from the novel functioning of the separator. In refrigerating systems heretofore proposed employing a plurality of refrigerants, extreme difficulty has been encountered in separating 100 the refrigerants so that they may be again condensed and fed into the evaporator in liquid form. Unless the refrigerants are separated, the apparatus cannot function to produce refrigeration for it is obvious that if 105 gaseous ammonia collects in the propane condenser C₂ to the extent that the gaseous mixture therein is the same as that in the evaporator E then the propane cannot condense in condenser C₂ at a temperature higher than 110 it evaporates in the evaporator. To obviate this difficulty it is proposed, in accordance with the present invention, to separate the two refrigerants by gravity and since they 115 are practically immiscible in their liquid phases very efficient separation can be effected in this manner. But before they can be separated by gravity however, it is first necessary to reduce them to their liquid phases. This 120 is accomplished in accordance with the invention, by causing the ammonia to be absorbed in a weak solution while at the same time the gas deprived of a large portion of 125 its ammonia content is maintained at a low 130

enough temperature to condense the propane. Furthermore after the propane has been separated it must be again returned to the evaporator. In the present case this is 5 done by causing it to be vaporized and fed into the condenser C₂. The separator S, together with the associated jackets thus provides a compact and unitary assembly for accomplishing all of these functions.

10 Since the drawings is only diagrammatic in nature it is obvious that in constructing an apparatus in accordance with the principles of the invention, various expedients may be resorted to and various changes may be 15 made in the arrangement and construction of the various parts without departing from the spirit of the invention. Various kinds of rectifiers, generators, condensers, etc., may be substituted for those shown and various 20 types of pumps or ejectors substituted for the gas lift pump 16.

As illustrating a somewhat different construction for carrying out the principles of the invention reference may be had to Figure 2 in which the general arrangement and construction of the various parts of the apparatus is similar to that of Figure 1 but in which a different form of generator, separator and pumping means for the absorption 25 solution is illustrated. In this figure the rectifiers, condensers and evaporator are identical with those of Figure 1 and need not be further described here. However, because of the different absorber structure, the condensers should be a greater distance above the 30 evaporator. For purposes of illustration the pipes 21, 38, 25, 27 and 28 are shown broken.

The generator G₂ of this figure has no gas 35 lift pump 16 therein, but in place thereof a coil 116 is provided in the conduit 141 leading into the lower portion of the separator S₂. The conduit 133 from the evaporator is connected to the coil at its lower end. By this means gas generated within the evaporator causes a circulation of the absorption 40 solution, the action being the same as that in the coil 29 and pipes 27 and 28 of Figure 1 of the copending application of Altenkirch, Serial No. 99,890, filed April 5, 1926, for 45 "absorption machines." As this gas from the evaporator meets with the solution coming through the lower portion of pipe 141 connected with the outer tube of the heat exchanger 140, it causes this liquid to rise 50 through the coil 116 into the separator S₂. From the separator the solution flows out through the pipe 139 through the inner tube of the heat exchanger 140, into the boiler 55 through the pipe 115 and from there back to the outer coil of the heat exchanger through the pipes 123, a heating coil 144 and the conduit 142. Since the direction of circulation is upward both in the generator and in the 60 separator the circulation is aided by thermo-

siphon action and by the generation of bubbles which pass upwardly in the generator. Essentially the separator S₂ functions the same as separator S of Figure 1, its lower portion being cooled by the cooling tank 145 70 and its upper portions being heated by the coil 144. The directions of flow of the absorption solution through the separators are opposite in the two cases, however.

Since the pressure in the evaporator of Figure 2 must be somewhat higher than that necessary in Figure 1, because of the greater liquid head to be overcome in the separator, it is necessary that the pipes 27 and 28 be 80 long enough to permit columns of liquid to form therein of sufficient height to balance the head in the separator. For this reason the condensers of Figure 2 must be a greater distance above the evaporator than that necessary in Figure 1. 85

It is also necessary to charge the apparatus of Figure 2 with more propane than that employed in the arrangement of Figure 1, since the separator S₂ should at all times, have enough liquid propane therein to extend 90 from a level just below the coil 144 to a level near the top of the separator.

It will be obvious to those skilled in the art that various other changes may be made without departing from the spirit of the invention or the scope of the annexed claims. For example the vessels may be made of different shapes and dimensions so long as they do not interfere with the intended circulation and liquid levels. It is also within the scope of the invention to control the circulation of the refrigerants or the absorption solution by providing suitable regulating valves in the various conduits and to control the application of heat to the generator and absorber. This may, for example, necessitate the provision of a conduit connected in parallel with the jacket 44 between the pipes 23 and 42 with 100 suitable valves for regulating the amount of warm solution which flows through the 105 jacket. 110

I claim:—

1. In a refrigerating system of the absorption type employing a plurality of refrigerants, the combination of a generator for expelling one refrigerant from an absorption solution, an absorber-separator, means for feeding a vapor mixture of said refrigerants into said absorber-separator, means for circulating the absorption solution between said generator and said absorber-separator to cause one refrigerant to be absorbed and another condensed in said absorber-separator and a jacket surrounding a portion of 115 said absorber-separator and forming part of said absorption solution circulating means for causing the absorption solution to heat said portion and vaporize the condensed refrigerant in said absorber-separator. 120

125

130

2. In an absorption refrigerating system employing two refrigerants, the combination of a generator adapted to expell one of said refrigerants from an absorption solution, a vessel for separating said refrigerants after they have become mixed, means for circulating an absorption solution between said generator and said vessel to cause one refrigerant to be absorbed and the other condensed in said vessel and means for causing the solution to pass around a portion of said separating vessel before it is passed into the interior thereof to convey heat therefrom to the generator and thereby vaporize the condensed refrigerant therein.
3. In a refrigerating system having a generator and an absorber and employing two refrigerants, the method of vaporizing one refrigerant from an absorption solution in said generator and another refrigerant from its liquid phase in said absorber which includes the steps of applying heat directly to said generator, circulating absorption solution between said generator and said absorber and causing said absorption solution to give up heat to a portion of said absorber before mixing directly with the fluid therein.
4. The method of producing refrigeration including the steps of feeding two different refrigerants in liquid phase into an evaporator, conducting the vaporized refrigerant from the evaporator into a separating vessel, causing one refrigerant to be absorbed in an absorption liquid and the other to be condensed in said vessel, separating the condensed refrigerant from the absorption solution by gravity, conveying the enriched absorption solution to a generator, applying heat to said generator to drive off the absorbed refrigerant and conveying the weakened absorption solution back to the absorber while causing a transfer of heat from the weakened absorption solution to the fluid in the absorber as the weakened absorption solution passes on its way to the absorber to thereby vaporize the refrigerant which has been condensed in said absorber.
5. In an absorption refrigerating system employing two refrigerants, the combination of an evaporator adapted to cause the two refrigerants to evaporate, an absorber-separator, a generator adapted to expel one of said refrigerants from an absorption solution and means for circulating absorption solution between said absorber-separator and said generator to cause one refrigerant to be absorbed and the other condensed in said absorber-separator, said circulating means including a device for causing the absorption solution to pass in heat transfer relation with a portion of said absorber-separator before it passes into direct contact with the fluids therein and thereby transfer heat from said generator to a portion of said absorber-separator to vaporize the condensed refrigerant therein.
- Signed at North Canton, in the county of Stark, and State of Ohio, this 23rd day of January, A. D., 1930. 70
- STANLEY R. CUMMINGS.
